UNITED STATES PATENT OFFICE.

ERNEST SAUTTER, OF PARIS, FRANCE.

MEANS FOR CLOSING RECEPTACLES.

No. 852,981.

Specification of Letters Patent.

Patented May 7, 1907.

Application filed November 28, 1906. Serial No. 345,531.

To all whom it may concern:

Be it known that I, ERNEST SAUTTER, a citizen of the Confederation of Switzerland, residing in Paris, in the Republic of France, and whose post-office address is 56 Rue de La Victoire, Paris, have invented a new and useful Improvement in Means for Closing Receptacles, which improvement is fully set forth in the following specification.

- 10 This invention has for its object an arrangement for closing any type of receptacles, bottles, flagons, jars, pots and the like, and particularly conical drinking glasses having a smooth edge.
- 15 The method of closing is based on the reaction of two conical surfaces pressing against one another (under the influence of an elastic force) so that the large end of the one tends to approach the small end of the other. In 20 order to effect this, the present arrangement consists of a metal capsule, with waved or corrugated sides, in the bottom of which is an elastic washer, and on which a smooth cylindrical metal locking ring curved at both 25 its edges or at its upper edge only, is applied by clamping or otherwise. The waves or corrugations of the sides begin a short distance from the top and become larger toward the edge, so as to present to the exterior a 30 substantially conical surface, the inside being cylindrical. It will be seen that if a capsule of this kind with an elastic washer and a locking ring is placed on the conical mouth of a receptacle to be closed, and pressure is exerted 35 on the capsule, the locking ring being put over it, the corrugated walls of this capsule will be bent inward and be pressed into close contact with the mouth of the receptacle, the outward surface thus becoming cylindrical & the inner surface will be made conical by the mouth of the receptacle. The action 40 of the joint and the elasticity of the corrugations of the capsule keep the receptacle hermetically closed. The downward movement 45 of the locking ring is stopped by its upper curved edge. The locking ring can be placed in position by any other suitable means such as by a strap capable of deforming the capsule in the same way. The locking 50 ring is prevented from coming off, either by curving in the lower edge against the lower edge of the capsule, or by any appropriate means. This curving in of the edge can be effected either by the natural elastic- 55 ity of the metal of the locking ring or by giving it a hooked shape, or by the partial or

total turning under of the lower curved edge by the machine which effects the closing. The certainty of closing is thus assured. The vessel is opened by bending back the curved 60 edge of the locking ring & raising the capsule thus freed.

This arrangement of closing is equally applicable to receptacles having a cover of their own. In this case the capsule is cut away 65 and is placed direct on the cover and the elastic packing is placed between the cover and the receptacle itself.

In the drawings which show examples of carrying out the invention: Figure 1 shows 70 separately in perspective the different elements used in closing. Fig. 2 is a section on a larger scale of the elements in position ready for closing. Fig. 3 is a similar section with the curved edge of the locking ring under 75 the capsule. Fig. 4 is a similar section showing the curved edge pressed farther in. Figs. 5, 6, 7 are views of the capsule showing different forms which can be used for making the corrugations or folds of the capsule. Figs. 80 8, 9 and 10 are sectional views of modified forms of closures.

The different elements of the closure which are placed on the conical mouth *a* of the receptacle to be closed, are the elastic washer *b* 85 forming the joint, the capsule *c* whose sides have corrugations *d*, which begin a short distance from the top and the locking ring *e* which locks the capsule.

In the case where the locking ring is put in 90 position by clamping, the washer *b* is first placed in the capsule *c*, and when the receptacle is about to be closed, the different elements are in the position shown in Fig. 2. The locking ring *e* having its ends fastened 95 together by an ordinary hooked joint, such as is shown and having at its lower end a curved edge *f* passes freely as far as the position shown in the figure. In order to effect the closing it is forced into place in such a 100 way as to turn under the corrugations *d* of the capsule which press firmly against the mouth of the receptacle, thus causing a tendency of the capsule to come close against the edge of the opening, that is to say to squeeze 105 the joint and to make the closing hermetical. In this movement the locking ring can be guided in order to avoid deforming it. At the end of its travel, the end *g* of the curved lower edge *f* of the locking ring hooks under 110 the corrugations *d* of the capsule, owing to its elasticity, as is shown in Fig. 3, and it is

thus rendered impossible to open it without opening out the curved edge, and so spoiling the locking ring. The closure obtained cannot thus be tampered with.

- 5 The curving in of the corrugations by the end *g* of the curved edge *f* of the locking ring can be made more complete by acting on this curved edge during the operation of closing by deforming it and making it pass farther 10 under the corrugations of the capsule as is shown in Fig. 4.

The folds of the capsules can take different forms without modifying any of the other parts described. The forms shown in Figs. 15 5 and 6 or similar forms will be used when great rigidity is wanted, for closing thick and strong receptacles. The form shown in Fig. 7 and similar forms will however be adopted when greater pliability is required 20 as for example for closing thin glasses.

An annular washer can be placed in an appropriate opening of the capsule; in addition, in order to improve its appearance, the upper end of the capsule can have a groove on 25 which the edge of the locking ring will lie. In the case of an annular washer contact between the capsule and the matter contained in the receptacle can be avoided by fastening on to the lower face of the annular washer a 30 disk *i* of tin or other suitable substance.

In the case of closing a receptacle having its own cover the annular washer is placed between the receptacle and its cover and pressed by means of a capsule having its center cut away and with corrugated or wavy 35 sides, held by the arrangement described above.

Having now particularly described and ascertained the nature of my said invention 40 and in what manner the same is to be performed, I declare that what I claim is:

1. An improved closure for receptacles, comprising a capsule arranged to embrace the mouth of the receptacle, in combination 45 with an annular band surrounding the capsule, the band having an inturned lower edge to snap under the lower edge of the capsule.

2. An improved closure for receptacles, comprising in combination, a receptacle having smooth sides a capsule with flaring corrugated walls arranged to embrace the mouth 50 of the receptacle, and an annular band bearing upon the top of and surrounding the capsule and pressing inwardly upon the corrugations.

3. An improved closure for receptacles, comprising a capsule with flaring contractible walls arranged to embrace the mouth of the receptacle and provided with spaced inward extensions, in combination with an annular band surrounding the capsule and bearing inwardly thereon, the band having an in-turned lower edge to snap under the lower edge of the capsule. 60

4. An improved closure for receptacles, 65 comprising a capsule with flaring corrugated walls arranged to embrace the mouth of the receptacle, and a washer resting upon the edge of the receptacle mouth within the capsule, in combination with an annular band 70 surrounding the capsule, the band having an in-turned lower edge to snap under the lower edge of the capsule.

5. An improved closure for receptacles, comprising a capsule with expansible walls 75 arranged to embrace the mouth of the receptacle and provided with spaced inward extensions, and an elastic washer resting upon the edge of the receptacle mouth within the capsule, in combination with an annular band surrounding the capsule and bearing inwardly by means of the inward extensions upon the receptacle, the band having an in-turned lower edge to snap under the lower edge of the capsule. 80

6. The combination, with a receptacle having smooth upwardly flaring sides, of a capsule with corrugated walls arranged to embrace the mouth of the receptacle, a washer resting upon the edge of the receptacle mouth 90 within the capsule, and an annular band surrounding the capsule and bearing inwardly upon the corrugations.

7. The combination, with a receptacle having smooth upwardly flaring sides, of a 95 capsule with corrugated walls arranged to embrace the mouth of the receptacle, a washer resting upon the edge of the receptacle mouth within the capsule, and an annular band surrounding the capsule and bearing inwardly 100 upon the corrugations, said band having an in-turned lower edge to snap under the lower edge of the capsule.

In testimony whereof I have signed this specification in the presence of two subscribers. 105

ERNEST SAUTTER.
